UNITED STATES PATENT OFFICE.

MONTAGUE STANLEY NAPIER, OF CANNES, FRANCE.

PISTON.

Application filed October 26, 1920. Serial No. 419,715.

To all whom it may concern:

Be it known that I, MONTAGUE STANLEY NAPIER, a subject of the King of England, and residing at Cannes, Alpes Maritimes, in France, have invented certain new and useful Improvements in Pistons, of which the following is a specification.

This invention relates to pistons more particularly pistons intended for use in internal combustion engines which are formed wholly or as to their skirts of aluminium or aluminium alloy and has for its object to provide a construction which will obviate that movement of the piston against the walls of the cylinder which is commonly referred to as "slap" or "tap."

Where the piston is constructed of the same metal as is employed in the formation of the cylinder within which the piston is to move the occurrence of piston "slap" is avoided by allowing only a small clearance between the exterior of the piston and the inner wall of the cylinder. In the case of a piston constructed of aluminium or aluminium alloy or where the piston skirt is formed of this metal in the usual type of piston it is impossible to make the clearance between the piston and the cylinder so small as to prevent "slap" from taking place owing to the difference in the coefficients of expansion of the aluminium or aluminium alloy and of the steel cylinder. "Slap" is considered to be due to the movement of the skirt of the piston against the walls of the cylinder while the head of the piston is prevented from such movement by the piston rings. It is apparent that the above mentioned defect may be overcome if the expansion of the skirt can be regulated to conform with the expansion of the cylinder. This end is attained by the present construction.

According to this invention the skirt of the piston is slit longitudinally or similarly formed and the minimum necessary clearance between the skirt and cylinder is maintained by means of a complete or unbroken ring which is formed of a metal which has a coefficient of expansion different from that of the metal of the skirt and substantially the same as the coefficient of expansion of the metal of which the cylinder is formed. The aluminium or aluminium alloy skirt is slit longitudinally for a substantial part of its length and a complete ring is provided which is formed of a metal having the de-

sired coefficient of expansion the ring being disposed in the skirt and fixed thereto towards its outer end but so that the ring will not be in contact with the cylinder wall. 60 Thus the skirt may be slit longitudinally in two or more places and a single complete ring of steel, iron or like metal is fixed within the skirt at or near its outer end or actually within a thickened end part of the skirt. 65 The coefficient of expansion of the metal of which the ring is formed is such that the diameter of that part of the skirt which lies adjacent to the ring will be determined by the expansion of the ring which will correspond with the expansion of the cylinder so that only the clearance necessary to permit of the desired sliding fit of the piston within the cylinder will be maintained. 70

The invention may be carried out in various ways but the accompanying drawings illustrate by way of example several alternative constructions that may be adopted.

In these drawings:—

Figure 1 is a longitudinal sectional elevation of one construction of the improved piston.

Figure 2 is an elevation of the same.

Figure 3 is a longitudinal section of the skirt portion of a piston showing an alternative construction.

Figures 4 and 5 are views similar to Figure 3 showing other alternative constructions.

The piston comprises a head A and a skirt B formed integral therewith and having bosses C adapted to carry a gudgeon pin. The piston is constructed wholly of aluminium or aluminium alloy and the skirt B is slit by making longitudinal cuts D therein, 90 these cuts being conveniently four in number and disposed preferably at equal distances apart around the skirt. 95

Referring to the construction shown in Figures 1 and 2, a single complete ring E of cast iron, steel, bronze or other suitable metal having the necessary coefficient of expansion is inserted into the end of the skirt B and is there fixed in some suitable manner as for example by rivets F. A greater or less number of slits D may be provided in the skirt B according to the dimensions of the piston and these slits may be spaced apart as found desirable with respect to those portions of the circumference of the skirt which are subjected to the greatest wear. The length of the slits D may vary 105 110

but conveniently they extend from the end of the skirt to or slightly beyond the neighbourhood of the plane in which lies the gudgeon pin axis. As will be seen the inserted ring E is in this case flat and has substantially the same thickness as the skirt and it is placed within the skirt B so that the one edge of the ring E and the end of the skirt B coincide.

10 In the alternative construction shown in Figure 3 the ring E is thickened at one edge or has a small inwardly directed flange E' formed at that edge. The ring is disposed so that the flange edge E' lies at the end of 15 the skirt B.

In the construction shown in Figure 4 a single ring E is inserted in the end of the skirt B but this ring is of greater thickness and less width than the ring E employed 20 in the construction shown in Figure 1.

In the arrangement shown in Figure 5 the end of the skirt B is thickened as at B' on the inner side so as to form an annulus of substantial dimensions. The longitudinal 25 slits D are carried through this thickened annulus and in the end face of the thickened part there is formed a recess in which is placed a ring E which in this case may be of square section. The ring E may 30 be kept in place by riveting or by otherwise connecting it to the divided portion of the skirt B.

In either of the above described constructions the expansion of the skirt is controlled 35 or determined by the expansion of the ring E and since the ring will expand in substantially the same way and to the same extent as the cylinder G in which the piston lies the aluminium skirt will have its external diameter maintained substantially 40 constant in relation to the diameter of the cylinder. Thus the advantage of an aluminium bearing surface is maintained without the disadvantage which results from the 45 aluminium or aluminium alloy having a coefficient of expansion which differs from that of the metal of which the cylinder is formed.

The dimensions and form of the ring E may vary as found desirable and as shown 50 in the several constructions illustrated in the accompanying drawings and described above. The details of construction may be modified as desired and the invention may be applied to pistons of various types and 55 either where the piston is formed wholly of aluminium or aluminium alloy or where the skirt is formed of this metal and is attached to a steel, iron or other head.

What I claim as my invention and desire 60 to secure by Letters Patent is:—

1. In a trunk piston the combination of a skirt portion and having in it a plurality of slits extending longitudinally from its outer end for a substantial part of its length 65 towards the piston head, a continuous un-

broken metal ring member having a coefficient of expansion differing from that of the metal of which the skirt is formed, and means whereby the ring member is attached to the skirt adjacent to the outer end 70 of the latter, the ring member being so formed and positioned with relation to the skirt that the ring will not be in contact with the wall of the cylinder in which the piston is used but will be operative to maintain substantially constant the minimum necessary clearance between the skirt and the cylinder wall as set forth.

2. In a trunk piston the combination of a head and a skirt portion formed integral 80 therewith having a plurality of slits extending longitudinally through the skirt from its outer end for a substantial part of its length towards the piston head, a continuous unbroken metal ring member having a coefficient of expansion which is different from that of the metal of which the skirt is formed but substantially the same as that of the metal of the cylinder in which the piston is used, and means whereby the ring member is attached to the skirt adjacent to the outer end of the latter, the ring member being so formed and positioned with relation to the skirt that the ring will not be in contact with the wall of the cylinder 90 in which the piston is used but will be operative to maintain substantially constant the minimum necessary clearance between the skirt and the cylinder wall as set forth.

3. In a trunk piston the combination of a skirt portion having in it a plurality of slits extending longitudinally from its outer end for a substantial part of its length towards the piston head, a continuous unbroken metal ring member having a coefficient of expansion which is substantially the same as that of the cylinder in which the piston is to be used but differs from that of the metal of which the skirt is formed, and means whereby the ring member is attached to the skirt adjacent to the outer end of the latter, the ring member being so formed and positioned with relation to the skirt that the ring will not be in contact with the wall of the cylinder in which the piston is used but will be operative to maintain substantially constant the minimum necessary clearance between the skirt and the cylinder wall as set forth.

4. In a trunk piston the combination of a skirt formed of aluminium and having in it a plurality of slits extending longitudinally from its outer end for a substantial part of its length towards the piston head, a continuous unbroken metal ring member having a thickening at one edge on its inner side the ring being formed of a metal having a coefficient of expansion differing from that of the metal of which the skirt is formed, and means whereby the ring mem- 130

- ber is attached to the skirt within the latter and adjacent to its outer end, the ring member fitting within the end of the skirt and being operative to maintain substantially 5 constant the minimum necessary clearance between the skirt and the cylinder wall as set forth.
5. In a trunk piston the combination of a head, a skirt formed integral with the 10 head, bosses adapted to carry the gudgeon pin formed in the skirt intermediate in its length, a plurality of slits extending through the wall of the skirt from its outer end towards the piston head and terminating in 15 the neighbourhood of the gudgeon pin bosses the slits being spaced apart around the skirt, a continuous unbroken metal ring member having a coefficient of expansion differing from that of the metal of which the skirt is 20 formed, and means whereby the ring member is attached to the divided parts of the skirt adjacent to the outer end of the latter, the ring member being in contact with the inner side of the divided parts of the 25 skirt and being operative to maintain substantially constant the minimum necessary clearance between the skirt and the cylinder wall as set forth.
6. In a trunk piston the combination of 30 a skirt portion having in it a plurality of slits extending longitudinally from its outer end for a substantial part of its length towards the piston head, a continuous unbroken metal ring member having a smooth 35 periphery adapted to lie within the skirt and at one edge a thickening constituting an inwardly directed flange, the ring being formed of a metal having a coefficient of expansion which is different from that of the 40 metal of which the skirt is formed but substantially the same as that of the metal of the cylinder in which the piston is used, and means whereby the ring member is attached to the skirt within the latter and adjacent 45 to its outer end, the ring member being operative to maintain substantially constant the minimum necessary clearance between the skirt and the cylinder wall as set forth.
7. In a trunk piston the combination 50 with a skirt portion slotted longitudinally of a continuous unbroken metal ring having a coefficient of expansion differing from that of the metal of which the skirt is formed, said ring being secured within the skirt portion and being adapted to maintain substantially constant the minimum necessary clearance between the skirt and cylinder wall, as 55 set forth.
8. In a trunk piston the combination with a skirt portion of aluminum provided with 60 one or more longitudinally extending slots of a continuous unbroken metal ring having a coefficient of expansion differing from that of the metal of the cylinder wall, said ring being secured within the slotted portion of the skirt and being adapted to maintain substantially constant the minimum necessary clearance between the skirt and cylinder 65 wall, as set forth.
9. In a trunk piston the combination with a skirt portion of aluminum and slotted longitudinally, of a continuous unbroken iron ring having a coefficient of expansion substantially the same as that of the iron cylinder wall, said ring being secured within the slotted skirt and being adapted to maintain substantially constant the minimum necessary clearance between the skirt and cylinder 70 wall, as set forth.
10. In an internal combustion engine, the combination with the engine cylinder of a piston in said cylinder having a skirt portion slotted in a generally longitudinal direction and a continuous metal ring within 75 the skirt portion having a coefficient of expansion substantially the same as that of the cylinder wall, said ring being secured to the skirt and being adapted to maintain substantially constant the minimum necessary 80 clearance between the skirt and cylinder wall, as set forth.
11. In a trunk piston the combination with a skirt portion slotted so as to be expandible and contractable under the influence of a control member, of a rigid control member within the skirt and secured thereto in such manner as to effectively control the diametrical expansion and contraction of said skirt, said control member having a 85 coefficient of expansion different from that of the skirt, for the purpose set forth.
12. In a trunk piston the combination with a skirt portion slotted so as to be expandible and contractable under the influence of a control member, of a rigid control member within the skirt and secured thereto at a plurality of points whereby diametrical expansion and contraction of the skirt due to changes in temperature is effected without distortion of the skirt from a truly circular form in transverse section.

In testimony whereof I have signed my name to this specification.

MONTAGUE STANLEY NAPIER.
